UNITED STATES PATENT OFFICE.

ACHILLE KAISERMAN AND ALBERT ZAUGG, OF HIGHLAND PARK, MICHIGAN; SAID ZAUGG ASSIGNOR TO SAID KAISERMAN.

BURNER.

Application filed July 1, 1922. Serial No. 572,184.

To all whom it may concern:

Be it known that we, ACHILLE KAISERMAN and ALBERT ZAUGG, citizens of Switzerland, and residents of Highland Park, in the county of Wayne and State of Michigan, have invented a new and Improved Burner, of which the following is a description.

Our invention relates to burners and more particularly to a burner for use in a heating furnace and adapted to burn crude oil as a fuel.

The general objects of our invention are to provide a burner for the indicated purpose improved in various particulars where-
15 by to increase the efficiency in the applicaton of the heat and looking to the effective regulation of the fuel and air.

The nature of the invention and its distinguishing features and characteristics will 20 clearly appear as the description proceeds.

Reference is to be had to the accompany-
ing drawings forming a part of this specifi-
cation, it being understood that the draw-
ings are merely illustrative of one example
25 of the invention.

Figure 1 is a side elevaton of the burner and its appurtenances embodying our invention illustrating the same installed in connec-
30 tion with a furnace shown partly broken
away and in section;

Figure 2 is a plan view, the furnace being in horizontal section, parts of the burner being broken out;

Figure 3 is a vertical section through the
35 burner proper;

Figure 4 is a vertical section through the
fuel reservoir;

Figure 5 is a plan view of the fan driven
by the draft in the furnace, the view being
40 indicated by the arrows 5-5;

Figure 6 is a plan view of the upper plate
of the air regulator, the plane of the view
being indicated by the line 6-6, Figure 3;

Figure 7 is a plan view of the lower ad-
45 justable plate of the air regulator, the plane
of the view being indicated by the line 7-7,
Figure 3;

Figure 8 is a horizontal section through
the fuel reservoir as indicated by the line
50 8-8, Figure 4;

Figure 9 is a detail in vertical section of
the operating means for the lower adjustable
plate of the air regulator, the section being
55 indicated by the line 9-9, Fig. 3;

Figure 10 is a vertical section through the

thermostat forming part of the assemblage and controlling the air regulator;

Fig. 11 is a front elevation of the ther-
mostat;

Figure 12 is a detail side elevation of a 60
valve assemblage to be referred to;

Figure 13 is a section on the line 13-13,
Figure 12;

Figure 14 is a section on line 14-14; 65
Figure 13;

Figure 15 is a section on line 15-15,
Figure 12.

In the illustrated example of our im-
proved burner a pan 15 is provided rigidly
sustained in horizontal position by legs 16 70
which are in two sections, the opposed
threaded ends 17, 18 of which engage in
threaded holes in the pan 15. The upper
ends of the legs have shoulders 19 on which
the burner shell 20 rests at the top of the 75
burner, said shell having a suitable cover 21.
The pan has an annular series of holes 22
which receives approximately U-shaped
wires 23 on which rests an asbestos ring 24.

The pan 15 and its asbestos ring 24 are in 80
the plane approximately of the plane of the
furnace grate. The pan 15 has an open cen-
ter for the draft so that the draft will cause

to be turned a fan 25 suitably secured to the
upper end of a spindle 26, the lower end 85
of which is centered in a step bearing 27 in a
fitting 28 through which the liquid fuel is

delivered as hereinafter explained, said fit-
ting being suitably fastened to the pan 15
as by a set screw 29 in an arm 15^a on said 90

pan. Beneath the fan 25 is an upper plate
30 having an annular series of air passages
and a lower plate 31 having an annular

series of air passages adapted to be brought
into register to a greater or less extent with 95
the openings of the plate 30. In forming
the openings in the lower plate 31 said plate

is formed with deflecting members 31^a at
each opening for directing air approxi-
mately tangentially. The plate 31 is at the 100

upper end of a flaring fitting 32 secured to a
sleeve 33 concentric with the spindle 26, the
lower end of said sleeve being threaded into

the arm 15^a. The lower plate 31 is rigid
with an outer tube 34 surrounding the sleeve 105

33 and sustained by a spring 35 coiled about
said sleeve and resting on the fuel supply

fitting 28. Thus, while oil rises upwardly
through the sleeve 33 from the fitting 28 air
rises through the pan 15 and passes up- 110

wardly outside of the tube 34 to the plate 31 through the same and the plate 30 to the fan 25, said fan being cup-shaped at the center and having flaring blades. The cup-shaped fan with its flaring blades and the flaring fitting 32 coat to direct the mixture laterally outward over a broad area and thereby produce an effective spreading of the flame.

10 A pilot light is provided by a gas pipe 37 having a tip or nozzle 38 in a nipple 39 secured to a shell 40 rising from the pan 15.

The plate 31 is regulated automatically from a thermostat as follows: The tube 34 carrying said regulating plate 31 has a flange collar at its lower end above the spring 35. Rigid with said collar is an arm 42 having an upturned hook 43 at its lower end engaged by an eye 44 on an operating rod 45. The rod 45 connects at its opposite end with one arm of a bellcrank lever 46 secured to any suitable fixed support and here shown as fulcrumed on a clamp band 47 pertaining to the fuel reservoir as herein-after explained.

The other arm of said bellcrank lever 46 has a weight thereon and secured to the arm is a wire or cable 49 connected with the thermostat and incidentally connected with the fuel regulator as hereinafter explained. Said wire 49 runs over a sheave 50 on top of a thermostat designated generally by the numeral 51 and comprising a suitably secured back plate attachable to any convenient wall or other suitable support in a room, the temperature of which is to be regulated. Wire 49 connects with a lever 52 of generally bellcrank form fulcrumed on the back plate of the thermostat. Said lever has a pointer pin 53 disposed vertically and an indicating head 54 has a scale of temperatures on its periphery and is secured to a shank 55 threaded into the lever 52 and subject to a coil spring 56 so that by adjusting the screw 55 the spring will be more or less stressed and thereby will oppose to a greater or lesser extent the rocking of the lever 52 according to the temperature desired. The thermostat includes a mercury cup 57 held rigid on bracket 58 of the thermostatic assemblage and a cylinder 59 containing alcohol and adapted to move vertically in the cup 57 on a guide pin 60 extending upwardly from the bottom of said cup. In the bottom of the alcohol cylinder 59 is a ball bearing 60 which, however, does not fit tightly on the guide pin 60 but only sufficient to give guided movement so that the mercury will be subject to the expansion of the alcohol to the cylinder 59. With the expansion of the mercury in the cup 57 and the alcohol in the cylinder 59 according to the temperature of the room the cylinder 59 will rise and will rock the lever 52, thereby permitting the weight 48 acting through the

rod 45, the arm 42 and the tube 34 to turn the air regulating plate 31 relatively to the plate 30 for cutting down the air supply.

In order that the air supply may be manually regulated we attach to the bellcrank lever 46 a second pull wire or cable 62 which runs over a sheave 63 on the back plate of the thermostat 51, the end of said wire 62 having suitable means to hold it in position, there being shown a ring 64 thereon adapted to be engaged with a fastening screw 65 or the like.

A fuel reservoir 67 is provided having an inlet pipe 68 in the bottom thereof and an outlet pipe 69 leading from the bottom to the fitting 28. From the inlet pipe 68 the fuel passes to the reservoir 67 through a strainer 70. In advance of the discharge end of the inlet pipe 68 the same is fitted with a partition 71 having a central fuel opening controlled by a disk valve 72 on the lower end of a spindle 73 advantageously made tubular, said spindle passing upwardly through the top 64 of reservoir 67. Above the lateral discharge outlets 73^a leading to the strainer 70 the top of the inlet pipe 68 is fitted with upper and lower disks 75 having registering openings through which the spindle 73 freely passes and a self-centering ring 77 is disposed between said upper and lower plates and snugly receives the spindle 73. A float 78 in the reservoir 67 is rigid with a sleeve 79 extending about the spindle 73 through the top 74 of the reservoir and on top of said sleeve 79 rests a lever 80 forked to pass at opposite sides of the spindle 73 and fulcrumed above as on a clamp bracket 81 on said stem. The forked end of the lever 80 has a slot and pin connection with a slide 82 on a vertical tube 83 through which the wire 49 passes, said tube being rigid with a bracket 84 on the reservoir 67. A stop screw 85 limits the downward movement of the slide 82 by contacting with the top 74 and a set collar 83^a on the tube 83 above the slide 82 limits the upward movement of said slide. Connection between the slide 82 and the wire 49 is established by a cross pin 86, the tube 83 being vertically slotted as at 87 to allow movements of the slide. 115

With the rising of the fuel in the reservoir 67 the float 78 will raise lever 80, bracket 81 and stem 73, thereby closing valve 72.

An upward movement of the lever 46 by a pull on the wire 49 or 62 will through said lever 46 exert a pull on the operating rod 45 which will give a turning movement to arm 42 and tube 44, thereby turning the air regulating valve plate 31 relatively to plate 30 and decrease the flow of air.

The fuel and air will be thoroughly mixed by the fan 25 as the fuel and air emerge at the under side of the fan blades, said fan being caused to revolve by the draft through the furnace.

The inlet pipe 60 is fed from a pipe 88 leading from any convenient source of supply (not shown), communication with the inlet pipe 68 being controlled by a valve 89. 5 The inlet pipe 68, valve 89, and the connection with the supply pipe 88 are sustained on a stand 90. On the stem of the valve 89 is a weighted arm 91 tending to close the valve. Said arm has an arcuate series of teeth 91^a 10 adapted to be engaged by a dog 92 on an arm 94 pivoted at one end on screw 93 secured to stand 90 by clamp 93^a. Arm 94 is normally sustained in the raised position by a spring 95, so that the dog 92 is in engagement with 15 one of the teeth 91^a. On the outer end of the arm 94 is a bucket 96 adapted to receive drip from a drip pipe 97 leading from a drip pan 98 disposed below the main pan 15 and here shown as sustained on the lower 20 end of the fitting 28. A drip pipe 99 leads from the main pan 15 to the auxiliary drip pan 98.

Upon an excess of fuel being fed to the burner, the fuel will fall to the pan 15 and 25 flow from the same through pipe 99 to the drip pan 98, thence by pipe 97 to the bucket 96 and when a predetermined quantity has been received by said bucket the tension of the spring 95 will be overcome, the arm 94 30 will be drawn downwardly, thereby releasing the dog 92 from the weighted arm 91 thus permitting said weighted arm to turn the valve 89 toward the closed position to the extent of one tooth and this operation 35 will be repeated if the fuel continues to accumulate in the bucket 96.

The gas pipe 37, fuel pipe 69, drip pipe 97, and pull rod 45, are in practice passed through the ash pit door of the furnace, the 40 stand 91 with the reservoir 67 being posi-

tioned in front of the furnace and the thermostat being positioned in the room above to be regulated.

We would state in conclusion that while the illustrated example constitutes a practical embodiment of our invention, we do not limit ourselves strictly to the exact details herein illustrated, since, manifestly, the same can be considerably varied without departure from the spirit of the invention as 45 defined in the appended claims.

Having thus described our invention, we claim:

1. In a burner of the class described, a fuel reservoir, an inlet pipe leading into the bottom of said reservoir, a valve controlling the discharge of fuel from said inlet pipe, a vertical spindle carrying said valve and extending above said reservoir, a float in said reservoir, a fuel delivery means, and means connected with said spindle and operative by said float to move the spindle for opening or closing said valve; together with means to conduct air to the discharge of said fuel delivery means, means to regulate the discharge of the air, and means to operate said air regulating means simultaneously with the movements of said spindle.

2. A burner including a fuel delivery means, air delivery means, an upwardly flaring discharge for the fuel delivery means, a tapering discharge for the air outside of the fuel delivery discharge, and a mixing fan above said discharges, said fan being formed with blades, each of the blades of the fan 70 being so shaped that a part of it lies parallel to the fuel discharge and another part overlies the air discharge.

ACHILLE KAISERMAN.
ALBERT ZAUGG.
